Attorneys.

UNITED STATES PATENT OFFICE.

MARTIN KROSCHEINSKY, OF BALTIMORE, MARYLAND, ASSIGNOR TO MARKEB MANUFACTURING COMPANY, OF BALTIMORE, MARYLAND, A CORPORATION OF MARYLAND.

METALLIC PISTON.

Application filed March 11, 1922. Serial No. 542,959.

To all whom it may concern:

Be it known that I, MARTIN KROSCHEINSKY, a citizen of the United States, residing in the city of Baltimore, State of Maryland, have invented certain new and useful Improvements in Metallic Pistons; and I do hereby declare the following to be a full, clear, and exact description of the invention, such as will enable others skilled in the art to which it appertains to make and use the same.

My invention relates to improvements in metallic pistons for use in internal combustion or steam engines, pumps, or the like, in which it is desirable to use a metallic piston and piston packing, and to keep the surface of the cylinder and of the piston which are in contact well lubricated without a needless waste of oil.

My present invention is more especially intended to provide a special form of metallic piston, which will be more fully understood after reference to the accompanying drawings, in which like parts are indicated by similar reference symbols throughout the several views and in which—

Figure 1 is a sectional elevation through a portion of the cylinder and enclosing jacket, the piston and packing rings being shown in elevation; and

Figure 2 is a sectional elevation showing the piston detached from the rest of the apparatus, and with the packing rings removed.

A represents the cylinder which may be provided with a suitable jacket A^o for cooling or heating purposes as the case may be.

My invention does not comprise the cylinder, and any suitable form of cylinder may be used as desired.

B represents the piston which is preferably of the usually hollowed-out or bell-shaped construction, with internally projecting bearings B' for the pin D to which the piston rod C is connected in the usual way; but the interior of the piston may be of any desired or preferable hollow shape, and the piston rod may be connected thereto in any convenient way. My invention relates more particularly to the exterior of the piston.

Beginning with the top of the piston, b is the usual coned face, in rear of which are the annular grooves b' and b³ separated from each other by the annular rib b².

The openings to receive the pin D extend out preferably to the outer edge of the piston, as shown at b⁴. Towards the rear, the piston is shown as provided with another groove b⁵ for the third packing ring. 60

The packing rings E, E' and E² may be of any suitable or preferred construction, preferably that shown in my co-pending application filed of even date herewith and entitled improvements in metallic piston 65 packing rings.

Towards the rear, the piston is provided with two conical surfaces b⁶, and b⁷ forming between the same a pocket b⁸ to catch the lubricant which is scraped into said pocket 70 from the inner walls of the cylinder by the scraping edge b⁹. Each of the walls which form the pockets b⁸ extends downwardly and inwardly at an inclination, and the wall b⁷, projects beyond the outer terminus of 75 the wall b⁶. The inner termini of the walls b⁶, b⁷, are slightly curved whereby the inner end of the pocket is rounded and arranged below the scraping edge b⁹, formed by the outer terminus of the wall b⁷. Any 80 excess of lubricant that accumulates in this annular pocket passes through the ports or holes b¹⁰ into the interior of the piston and falls down on the crank shaft bearings, not shown. The lower face of the piston is 85 tapered upwards and inwards, as at b¹¹, leaving a scraping edge b¹² which serves to scrape off any excess of lubricant adhering to the interior of the cylinder, and throws it down onto the crank shaft bearings as be- 90 fore described.

By the herein described construction a highly efficient lubrication of the parts of the cylinder, piston and piston rings in contact is secured, and at the same time the 95 supply of oil or other lubricant used is limited or controlled in such a way as to promote economy in the use of lubricant, and prevent charring of the oil in the cylinder. 100

I have shown three grooves for packing rings and three sets of metallic piston packing rings mounted in these grooves, which will steady the piston in its travel, and in a large measure prevent the lateral vibration of the same or "slapping" as it is called; but the number of grooves and corresponding sets of piston rings may be increased or decreased as desired, and yet come within the construction claimed. 105 110

It will be obvious that these and other modifications might be made in the herein described construction, and in the combination and arrangement of parts which 5 could be used without departing from the spirit of my invention; and I do not mean to limit the invention to such details except as particularly pointed out in the claim.

Having thus described my invention what 10 I claim and desire to secure by Letters Patent of the United States is:—

A metallic piston comprising a hollow body portion closed at its top and open

at its bottom and provided intermediate its ends with a peripheral V-shaped pocket 15 formed of an upper and a lower wall, each extending inwardly and downwardly at an inclination, said lower wall projecting beyond the outer terminus of the upper wall and forming an annular scraping edge and 20 said body portion further formed with ports disposed at an angle with respect to the axis thereof and opening outwardly through said upper wall above the bottom thereof.

MARTIN KROSCHINSKY.
